BALL MAKING MACHINE

Orien V. Osborne, Greenville, Ill.

Application December 13, 1938, Serial No. 245,531

7 Claims. (Cl. 80—18)

This invention relates to ball making machines and more particularly to a machine adapted for use in the formation of balls by the forging process.

5 An object of this invention is to provide a ball making machine wherein small irregular articles which are properly heated may be inserted in the intake portion of the machine and such objects will be rounded off during the passage thereof 10 through the machine until the objects attain the desired diameter and spherical configuration.

Another object of this invention is to provide a ball making machine of this type which is provided at the intake end thereof with laterally 15 movable die members which are provided with an irregular ball making surface or groove so that where the article being made into a ball has an irregular surface the configuration of the groove will tend to smooth out the surface of the article 20 so that the article will readily pass through the remaining portion of the machine and therein be formed into a sphere of suitable diameter.

A further object of this invention is to provide a plurality of spring pressed die members which 25 may be properly tensioned so as to exert the necessary pressure on the heated article in order to shape the article into a sphere or ball.

A still further object of this invention is to provide a die structure which includes stationary die 30 members and rotatable die members, the stationary die members being capable of adjustment toward or away from the rotatable die members.

To the above objects and to others which may hereinafter appear, the invention consists of the 35 novel construction, combination and arrangement of parts as will be more specifically referred to and as illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation of a ball making machine constructed according to an embodiment of this invention,

Figure 2 is a sectional view taken on the line 2—2 of Figure 1,

Figure 3 is a sectional view partly in detail taken on the line 3—3 of Figure 2,

50 Figure 4 is a fragmentary sectional view taken on the line 4—4 of Figure 1,

Figure 5 is a fragmentary sectional view taken on the line 5—5 of Figure 1,

Figure 6 is a plan view of one of the die members used with this machine,

Figure 7 is a plan view of another of the die members used with this machine, and

Figure 8 is a view showing in one position thereof the front elevation of a die adjusting plate and in another position thereof an end elevation of the same plate.

Referring to the drawings, the numeral 10 designates generally a base structure and the numerals 11 and 12 designate vertically disposed spaced apart plates forming a housing which are 10 secured to the base 10 by means of angle members 13 and 14 respectively. The angle members 13 and 14 have one leg thereof secured to the base plate 10 by means of fastening devices 15 in the form of rivets or the like and the other leg of the 15 angle members 13 and 14 is secured on the inner face of the plates 11 and 12 by means of bolts or fastening members 16. The plate 12 has a bushing or bearing 17 having a flange 18 which is secured to the outer side of the plate 12 by 20 means of bolts or fastening members 19. The two plates 11 and 12 are preferably rectangular in side elevation and these two plates are held in spaced apart relation by means of triangularly shaped corner members 20 which are secured to the plates 25 11 and 12 by means of bolts 21. A drive shaft 22 is journaled through the bearing 17 and the shaft 22 is adapted to be connected to a suitable source of power supply. The shaft 22 has a ribbed wheel or annular member 23 fixed thereto and this 30 wheel constitutes a carrier or support for a rotatable outer die member to be referred to. The wheel 23 is provided with a laterally extending endless flange 24 on one side thereof. The inner edge or face of the flange 24 is provided with a 35 right angularly disposed endless outer die member seat 25. An annular or ring-shaped outer die member 26 which is provided with an endless groove 27 on the inner periphery thereof is seated in the seat 25 being secured by means of bolts 28 40 or the like.

The groove 27 is substantially semi-circular in transverse section and forms one-half of a die structure for forming a ball or sphere. A primary set of endwise abutting stationary radially adjustable tensioned inner die members 29 of segmental contour and a secondary set of endwise abutting stationary radially adjustable tensioned inner die members 30 of segmental contour are disposed within the circle described by the outer 45 die member 26 and are also arranged in juxtaposition to the groove 27 of member 26. The leading one of the inner die members of the set 30 has its follower end abut the rear end of the follower outer die member of the set 29. The inner die 50 55

members 29 and 30 are secured to a plate 31 which is carried by a suspended supporting block or body member 32. The body member 32 is provided with a pair of spaced apart flanges 33 and 34 and the plate 31 is secured to the flange 33 by means of bolts 35. The flange 34 is secured to the plate 11 by means of bolts or fastening devices 36. The block or body member 32 is provided with a bore 37 through which the shaft 22 projects and a collar 38 is secured to the shaft 22 and abuts against a sleeve 39 which is integral with the body 32 and projects through an opening 40 provided in the wall or plate member 11. The shaft 22 is rotatable relative to the body or block 32.

15 The body or block 32 is provided with a plurality of circumferentially spaced apart plates 41 on the outer edges thereof which extend between the flanges 33 and 34 and if desired may be welded or otherwise fixedly secured to the flanges 33 and 20 34. A shoe 42 bears against the die 30 at the discharge end of the device and intermediate shoe members 43 extend against the abutting ends of the abutting die member 30 as shown in Figure 3.

The shoe or pressure member 42 is provided 25 with a stud 44 about which a spring 45 engages and the spring 45 is tensioned by means of a threaded member 46 having a collar 47 bearing against the inner end of the spring 45. The spring tensioning member 46 is threaded through a plate 41. The shoe 43 is constructed somewhat similar to the shoe 42 except that the head of this shoe 43 is longer. The shoe 43 has a stud 48 about which one end of a tensioning spring 49 engages. The spring 49 is tensioned by means of a threaded tensioning member 50 having a collar 51 bearing against the inner end of the spring 49. Each die 30 is provided on the inner side thereof with a lug 52 having an elongated opening 53 therethrough and the die adjusting and holding bolt 54 extends through the opening 53. The bolt 54 extends through plates 55 having a lug 56 loosely engaging in an opening 57 provided in each of the plates 11 and 31.

The die members 28 are preferably formed of 45 two portions 58 and 59, each having grooved portions 60 and 61 respectively, and the two die portions 58 and 59 are adapted to be held in face abutting relation by tensionable means including a bolt 62 which extends through the inner portions 50 of the two die members 58 and 59 and a spring 63 is disposed about the bolt 62 bearing at one end against the die member 59 and at the other end against an adjustable or tensioning nut 64. The bolt 62 and the spring 63 project outwardly or laterally through the plate 11, the plate 11 having a relatively large opening 65 through which the bolt 62 and the spring 63 may project. The die members 29 tensioned by means of shoe members 42^a and 43^a are similar to the shoes 60 42 and 43.

The shoe 42^a has a spring 45^a bearing thereagainst which engages about a stud 44^a and a threaded tensioning member 46^a having a collar 47^a bears against the inner end of the spring 45^a. The shoe 43^a is tensioned by a spring 49^a which is adjusted by an adjustable tensioning member 50^a. The threaded member 50^a has a collar 51^a fixed thereto which bears against the inner end of the spring 49^a. The outward movement of the die members 29 is limited by means of limiting bolts 66 extending through relatively large openings 67 provided in the die members 29 and these bolts 66 are radially adjusted by adjusting plates 68 having lugs 69 extending into openings 70 provided in the plates 11 and 31.

When the bolts 66 are tightly secured in the plates 11 and 31, the die members 29 are limited in their outward movement.

As shown in Figure 6 the grooves 60 and 61 in the die members 58 and 59 are of irregular configuration, the irregularities being both lateral and radial so that when a heated block 71 is inserted in the intake end 72, the irregular surface on the block or body 71 will roll over the irregular grooves 60 and 61 and have the sharp 10 corners thereof rolled out. In the present instance, there are provided two die members 29 which have an irregular groove in the outer portion thereof, but I do not wish to be limited to the particular number of irregularly grooved and 15 split members 29. There are also shown at least three die members 30 which are provided in the outer surface thereof with a smooth groove 73 so that the article 71 will have the outer surface thereof formed into a smooth surface which 20 will be symmetrical and in the present instance will be spherical in configuration.

Plate 11 is provided with a plurality of radially disposed openings 74 confronting the springs for the die tensioning shoes and the die tensioning 25 members and is also provided with an intake opening 75 adjacent the first die member 29. The plate 11 is also provided with a discharge opening 76 above the opening 75 and if desired suitable discharge means in the form of a chute or trough 30 may be extended into each opening 75 and 76.

The rear end of the groove formed in the forward inner die member of the set 29 registers with the forward end of the groove 73 in the forward inner die member of the set 30.

In the use and operation of this ball making machine, the heated article 71 is passed through the intake opening 75 and received in the intake groove portion 72 of the stationary ball forming die structure. The rotatable member 23 is rotated by the shaft 22 and as the rotatable member 23 rotates in a counter-clockwise direction as viewed in Figure 3, the article 71 will be forced into the grooves 60, 61 and the groove 27. The highest point of the grooves 60 and 61 is substantially deeper than the depth of the groove 73 in the die members 30 so that the heated article 71 will gradually be reduced in size or rolled to shape and will gradually be formed into a ball as it moves past the two stationary 50 die members 29. The pressure on these die members 29 may be properly adjusted by the tensioning members 50^a. As the annular die member 26 is rotated it carries therewith the hot ball member 71 which after passing the two die 55 members 29 will enter the groove 73 of the die members 30 which are adjusted toward the annular die member 26 by means of the die adjusting bolts 54. These bolts 54 limit the outward movement of the die members 30 so that the article 71 60 will not assume a lop-sided or oval configuration.

By providing the die members 29 in split form the initially rough shaped article 71 will be more gradually rolled to the desired configuration due to the fact that the two die portions 58 and 59 are tensioned against each other and are permitted by this tensioning to move apart slightly under the pressure of the springs 63.

What I claim is

1. In a machine for making spherical bodies, a suspended upstanding rotatable carrier having one side thereof provided with a laterally extended endless flange formed on its inner edge with an annular seat, an outer annular die member secured against said set and having its inner

edge provided with an endless groove, an up-standing suspended stationary supporting means encompassed in spaced relation by said outer die member, a housing common to said carrier and means having an intake opening and a discharge opening, a rotatable shaft extending through said housing, carrier and means fixed to said carrier and free of connection to said means, a primary set of endwise abutting stationary radially adjustable tensioned inner die members of segmental contour formed with continuous endwise registering grooves in their outer edges disposed in juxtaposition to the groove in the outer die member, a secondary set of endwise abutting stationary radially adjustable tensioned inner die members of segmental contour formed with continuous endwise registering grooves in their outer edges disposed in juxtaposition to the groove in the outer die member, the groove in the leading one of the secondary set of inner die members registering with the groove in the follower one of the primary set of inner die members, the leading one of the secondary set of inner die members having its leading end abutting the follower end of the leading one of the primary set of inner die members, means for connecting said sets of inner die members to said housing and said supporting means, and spaced shoes connected to and radially disposed relative to said supporting means, said shoes abutting against the inner edges of the said inner die members and being provided with adjustable tensioning means for said inner die members.

2. The invention as set forth in claim 1 having said supporting means in the form of an axially apertured polygonal-shaped block formed in its

outer edge with an endless groove, an apertured plate secured to one side of and extended from the block and spaced plates disposed circumferentially of the outer edge of said block and being formed with openings through which parts 5 of said shoes extend.

3. The invention as set forth by claim 1 having each of said die members of said primary set formed of a pair of lengthwise aligned resiliently connected sections, the sections of each 10 inner die member of the primary set having co-acting complementary means to provide the groove on the inner edge of the die member.

4. The invention as set forth in claim 1 having the walls of the grooves of the inner die 15 members of the primary set irregular throughout, the walls of the grooves of the inner die members of the secondary set smoothed throughout, and the wall of the groove of the outer die member smoothed throughout. 20

5. The invention as set forth in claim 1 having said means for connecting the sets of inner die members to said housing and said supporting means including plates for adjusting the inner die members. 25

6. The invention as set forth in claim 1 having the leading end of the outer die member of the primary set of inner die members aligning with and spaced from the follower end of the follower die member of the secondary set of inner 30 die members.

7. The invention as set forth in claim 1 having one side of said housing provided with spaced openings for access to the tensioning means carried by the shoes. 35

ORIEN V. OSBORNE.
